Specification for Design.

Patented Mar. 7, 1916.

Application filed June 10, 1915. Serial No. 33,399. Term of patent 14 years.

To all whom it may concern:

Be it known that I, ALFRED C. GILBERT, a citizen of the United States, residing in New Haven, in the county of New Haven and State of Connecticut, have invented a new, original, and ornamental Design for a Toy Building Element, of which the following is a specification, when taken in connection with the accompanying drawing.

In the drawing, Figure 1 is a front elevation of a toy building element embodying my design; and Fig. 2 is an end view of the same.

What I claim is:—

The ornamental design for a toy building element, substantially as shown.

ALFRED C. GILBERT.
